VAPORIZER FOR INTERNAL COMBUSTION ENGINES

Arnold Seidel, Berlin-Charlottenburg, Germany

Application May 5, 1932, Serial No. 609,433
In Germany May 6, 1931

12 Claims. (Cl. 261—18)

The present invention relates to improvements in a vaporizer for internal combustion engines, and more particularly to a vaporizer for multi-stage service, which is adapted to atomize heavy 5 oils and light fuels, such as benzene.

A characteristic of hitherto usually known carburetors was to produce only a coarse atomizing of the fuel-air mixture, but not to produce an ideal atomization thereof. This feature was not 10 objectionable in the case of carburetors for light fuels, such as benzene, but it is impossible to obtain a sufficient heavy oil service with such carburetors because the imperfect atomization causes the formation of condensates, which enter into 15 the cylinder and from the walls thereof into the crank case, where they produce a dilution of the lubricant.

One of the objects of my invention is to provide a vaporizer for atomizing liquid fuels to a 20 high degree to permit heavy oil service.

Another object of the invention is to provide means to impart an exceptional high speed to the fuel-air mixture.

Still another object of my invention is to provide 25 means to automatically change from benzene service to heavy oil service, as soon as the speed of the fuel-air mixture reaches the high degree which is necessary to ensure the atomization of the heavy oil, and to automatically change 30 over from heavy oil service to benzene service, if the speed of the fuel-air mixture becomes too low for the atomization of the heavy oil.

A further object of the present invention is to 35 provide means in the conduits of a multi-stage vaporizer, except the conduit of the first stage, which means prevent an undesired communication between the different valve chambers of the engine.

I accomplish the purposes of my invention with 40 a vaporizer for multi-stage service which comprises a float chamber provided with a fuel nozzle, a primary mixing channel into which said fuel nozzle opens, a plurality of main atomizers each having an injector slot at its narrowest cross-section and being open on one side to the air and on the other side connected to the intake manifold of the engine, each injector slot being connected to said primary mixing channel by a duct, a slot closure in the narrowest cross section of each 45 main atomizer and provided with splitting edges the latter being arranged substantially at right angles to said ducts, and conduits extending from said main atomizers. In order to obtain the automatic change from benzene service to heavy 50 oil service and vice-versa, I arrange an additional

float chamber provided with a fuel nozzle opening into a duct leading to the primary mixing channel, a change over element at the point of junction between said primary mixing channel and said duct, and means connected with said change over element and driven by means of the pressure in the conduit of the first stage and adapted to automatically move the change over element. 5

In the accompanying drawings which form a part of this specification and in which like characters of reference indicate the same parts:—

Fig. 1 is a vertical sectional view of a vaporizer taken on line 1—1 of Fig. 2;

Fig. 2 is another vertical sectional view of the 15 vaporizer shown in Fig. 1 taken on line 2—2 of Fig. 1;

Fig. 3 is a horizontal view partly in section of the vaporizer shown in Fig. 1 taken on line 3—3 of Fig. 1; 20

Fig. 4 is a top plan view of the slot closure of the vaporizer shown in Fig. 1 in a diminished scale;

Fig. 5 is a side view of another embodiment of 25 a vaporizer, partly a sectional view taken on line 5—5 of Fig. 6;

Fig. 6 is a vertical sectional view of the vaporizer shown in Fig. 5 taken on line 6—6 of Fig. 5;

Fig. 7 is a horizontal sectional view of the vaporizer shown in Fig. 5 taken on line 7—7 of Fig. 30 5 and

Fig. 8 is a top plan view of the slot closure of the vaporizer shown in Fig. 5.

Referring to Figs. 1 to 4 inclusive, the apparatus comprises a float chamber 6 for a heavy 35 fuel (heavy oil) and a float chamber 2 for a light fuel (benzene), the two chambers being arranged in the same horizontal plane. The float chamber 6 for heavy oil has a nozzle 5 which opens into a nozzle 100 inserted in a channel 101 for the primary mixture in advance of a rotatable change-over valve 9 provided with a longitudinal bore 10 closed on both ends and apertures 11, 11', 12 and 12' arranged in its wall. The float chamber 2 for the benzene has two nozzles 1 and 41, that 40 nozzle 1 opening into a nozzle 102 inserted in a channel 103 for the primary mixture. The nozzle 41 of the float chamber 2 for benzene serves for preparing the idle benzene-air mixture and opens into the channel 42 for the idle mixture. 50

In the position shown in Fig. 3 the apertures 11, 11' of the change-over valve 9 provide a connection between the primary mixing channel 101 and a narrow duct 7, which opens into an annular space 37 formed around the upper part 36 (Fig. 55

2) of the main atomizer. Said annular space 37 communicates with an injector-slot 104 arranged between the upper part 36 and the lower part 38 of the main atomizer at the narrowest cross-section thereof. The main atomizer 36, 38 is arranged in the narrow conduit 3 of stage I and may be controlled at its narrowest cross section by means of a slot closure 18, 19, which will be described hereinafter. The upper end of the 10 atomizer is open to the air. The conduit 3 branches into the narrow conduits 34 and 34' leading to the valve chambers of the motor (not shown). Additional atomizers 33 and 33' are disposed in said conduits 34 and 34' and serve to 15 remove any condensates which may be deposited on the smooth walls of the conduits.

A wide duct 8, in which a Venturi nozzle 105 is inserted, registers with the aperture 12' of the change-over valve 9 and opens into an annular 20 space 106 formed around the upper part 107 (Fig. 2) of the main atomizer of stage II. Said annular space 106 communicates with an injector slot 108 arranged between the upper part 107 and the lower part 109 of the main atomizer at the narrowest cross-section thereof. The main atomizer 107, 109 is arranged in the wide conduit 4 and may be controlled at its narrowest cross-section by the above mentioned slot closure 18, 19. The upper end of the atomizer 107, 109 is open to the 30 air. The conduit 4 branches into the wide conduits 27 and 28 connected with the valve chambers of the motor (not shown) and controlled by the throttling valves 25 and 26, which prevent an undesired communication between the valve 35 chambers of the motor through the conduits 4 and 3 of the stages II and I.

The rotatable change-over valve 9 is provided with a shaft 110 (Fig. 3), to the free end of which the upper end of a link 111 is secured. The lower end of said link is connected with a rod 112 of a piston 14 reciprocable in a cylinder 13 attached to the casing of the vaporizer. A spring 15 surrounding the rod 112 is interposed between the piston 14 and the right hand end of 45 the cylinder and tends to move the piston to the left hand side. A channel 16', 16, 17, 17' forms a connection between the right hand chamber of the cylinder and the conduit 3 of the stage I, so that a vacuum exists in said chamber, if the 50 channel 16', 16, 17, 17' is open during the operation of the vaporizer. Said channel is controlled by the above mentioned slot closure 18, 19.

A lever 113 fastened to the pin 110 of the rotatable change-over valve 9 carries a counter 55 weight 20 adjustably mounted on the free end of said lever. Said counter weight prevents oscillations of the piston 14 and valve 9 in harmony with the induction impulses in the conduits.

As mentioned above the two atomizers 36, 38 and 107, 109 of the stages I and II and the connecting channel 16', 16, 17, 17' are controlled by a slot closure which consists of two very thin plates 18, 19 sliding in guides 114 and 115 (Fig. 4). The plates are provided with holes 116-121, 60 which control the conduits of the stages I and II and the connecting channel 17. The holes 116 and 117 and 120 and 121 are of oblong form. Fig. 4 shows the slot closure in closed condition, that is the holes 116-121 are in such a position 65 relatively to each other, that the stages I and II and the connecting channel are completely covered by the plates 18 and 19. When it is desired to open the carburetor, a rod 24 is rotated by means of a Bowden cable 122 attached to one end 70 75 23' of a two-armed lever 23 secured to said rod,

so that a two-armed lever 123 mounted on the upper end of said rod 24 is rocked about its axis. Rollers 124, 125 mounted on the free ends of the lever 123 engage with recesses 126, 127 of the plates 18, 19 and shift these plates along their guides and against each other a distance corresponding to the rocking amount of the lever. During this shifting the holes of the plates 18 and 19 approach each other and at first the holes 116 and 117 and then the holes 120 and 121 overlap each other to such a degree, that the stage I and the connecting channel 17 are fully opened. At this time the stage II is still closed, as the holes 118, 119 do not register. During a further shifting of the plates 18, 19, the stage I and the connecting channel 17 remain in open condition due to the oblong form of the holes 116, 117, 120, 121, and the stage II will be opened, as the holes 118, 119 will overlap each other. When the rod 24 and the lever 123 are rocked in the opposite direction by means of the helical spring 121, said operations take place in reverse sequence.

The holes controlling the stages I and II form splitting edges, which are arranged substantially at right angles to the ducts 7 and 8 leading the primary mixture. The primary mixture flows simultaneously to all sides of the splitting edges, as the plates 18, 19 are arranged horizontally immediately below the injector slots 104 and 108. At the splitting edges the speed of the air coming from the open end of the atomizer is the actual absolute maximum air speed (about 100-200 m/sec.), as there is the narrowest cross-section of the atomizer, so that a perfect atomization will be obtained.

The lower end of the rod 24 carries a pin 129 engaging with an oblong aperture 130 of a sleeve 131 screwed to a shaft 132 carrying a lever 133. Said lever 133 is connected with one end of a link 134, the other end of which is connected with a lever 135 secured to a shaft 136 carrying the throttling valve 26. The shaft 136 also carries a toothed segment 137 meshing with another toothed segment 138 mounted on a shaft 139 carrying a throttling valve 25.

The idle benzene mixture flows through the horizontal channel 42, the vertical channel 43, the horizontal channel 43', the annular chamber 44 surrounding the atomizer 109, and the channel 43'' to the annular chamber 45 surrounding the atomizer 38, from which chamber 45 the idle mixture enters through openings 46 into the stage I behind the slot closure. The channel 42 has an enlarged part 42', into which additional air may enter through an aperture 47 controlled by a piston 48 movable in the part 42'. The aperture 47 may be closed by said piston 48, if a high percentage of idle mixture is desired for the starting operation.

The primary channels 101, 103 are provided with openings 40, 39 controlled by a valve 128. The adjustment of the valve 128 determines the amount of additional air coming to the primary mixture.

The vaporizer operates as follows: In order to obtain a normal speed of the motor, the plates 18 and 19 of the slot closure are shifted against each other to such a position, that the oblong holes 116, 117 and 120, 121 fully open the stage I and the connecting channel 16', 16, 17, 17', while the holes 118, 119 overlap each other only partly, so that a small elliptical opening is formed as shown in Fig. 3 and the stage II is opened only about $\frac{1}{3}$ of its width. Owing to the fact that a play exists in the connection be- 75

- tween the rod 24 and the linkage of the throttle valves 25, 26 by means of the oblong holes 130 the throttle valves 25, 26 are still in the position shown in Fig. 1 closing the wide conduits 27, 28. 5 The opening of the connecting channel 16', 16, 17, 17' causes the creation of the same vacuum in the right hand chamber of the cylinder 13 as the vacuum in the conduit 3 of stage I produced by the suction of the motor. As soon as 10 the vacuum in the stage I is high enough to ensure a perfect atomization of heavy oil, the same vacuum in the right hand chamber of the cylinder 13 causes a movement of the piston 14 against the spring 15 having a predetermined tension, so that 15 the change-over valve 9 is automatically rotated into the position shown in Fig. 3, in which the channel 101 of the heavy oil primary mixture is connected with the duct 7 leading to the main atomizer of stage I. 20 As mentioned above, the valves 25 and 26 close the conduits 27 and 28 in the described position of the slot closure, so that no vacuum is created in the conduit 4 of the stage II. The main atomizer 107, 109 of said stage, however, is open 25 to the air at its upper end and connected with the change-over valve 9 and the duct 7 through the injector slot 108 and the duct 8. Therefore, additional air enters through the open end of the main atomizer 107, 109, the duct 8 and the 30 bore 10 of the valve 9 to the primary mixture flowing from the channel 101 to the duct 7 and the stage I. Said additional air is forced to flow through the Venturi nozzle 105 in a direction opposite to the normal direction of flow, so that 35 the additional air will be throttled considerably. This throttling effect compensates in connection with an automatic regulation of the quantity of additional air the disproportionate output of the fuel nozzle 5. The quantity of additional air 40 passing through the duct 8 is determined by the pressure existing at the injector slot 108. During an opening of the stage II by means of a further movement of the lever 23 causing a full opening of the main atomizer 107, 109 and a 45 rotating of the valves 25 and 26 into open position, a gradually increasing vacuum will be produced at the injector slot 108 owing to the fact, that the motor now is able to draw over the stage II also. Thus, at first little additional air will 50 flow through the duct 8 into the duct 7, whereupon the admission of additional air entirely ceases and then the air and finally the fuel-air mixture will be drawn by the motor through the conduit 4 of the stage II and mixed with the 55 fuel-air mixture of the stage I in the valve chambers of the motor.
- Said additional opening of the stage II will be carried out, if a maximum speed of the motor or an acceleration of the car is desired. As soon 60 as the valves 25, 26 open the wide conduit 4 to the valve chambers of the motor, the vacuum in the conduit 3 of the stage I and in the cylinder 13 will drop, and as soon as the vacuum becomes 65 too little to enable an atomization of heavy oil, the spring 15 urges the piston 14 to the left hand side, so that the change-over valve 9 is rotated automatically into a position in which the channel 101 for heavy oil will be closed and the 70 channel 103 for benzene will be opened to the main atomizers by means of the aperture 12. The aperture 12' is of such a size, that the connection with the duct 8 will be retained, when the valve 9 is rotated into the position for benzene service.

In order to make the automatic change-over device inoperative if desired, a rotatable valve 21 is provided, which may be turned into such a position, that it connects the vacuum chamber of the cylinder 13 with the air, so that the spring 15 holds the piston 14 in its left hand position thus establishing the benzene service. An abutment lever 22 mounted on the shaft of the valve 21 comes into the path of the end 23' of the lever 23 and forms a stop for the latter, if the 10 valve 21 is rotated into the position to make the change-over device inoperative. Thus the abutment lever is adapted to limit the opening movement of the slot closure.

The embodiment of the vaporizer shown in 15 Figs. 5-8 inclusive is provided with two conduits 3 (stages I) working in parallelism and two conduits 4 (stages II) also working in parallelism. The vaporizer is adapted to supply the fuel mixture to two motors (not shown) having separate 20 intake conduits. The pair of narrow conduits 3 extends downwardly similar to the arrangement of the vaporizer shown in Figs. 1 and 2, while the pair of wide conduits is arranged opposite to the conduits 3 and extends upwardly. 25 There is only one float chamber 6 for heavy oil and only one float chamber 2 for benzene. The ducts 8 extend downwardly from the change-over valve 9, which controls the two ducts 7 and the two ducts 8. The ducts 8 open into the main 30 atomizers 107 and are provided with the Venturi nozzles 105. The conduits 4 are controlled by throttling valves 53 connected by a linkage to the valves 25 and 26. Therefore, the slot closure plates 18, 19 are provided merely with holes 116, 35 117 and 120, 121 controlling the pair of stages I and the connecting channel 16, 17 (see Figs. 7 and 8). The operation of the vaporizer is similar to the operation of the vaporizer as shown in Figs. 1-4, so that a detailed description is thought 40 to be superfluous. The slot closure 18, 19 simultaneously opens the two conduits 3, and the valves 54 simultaneously open the two conduits 4.

I have shown preferred embodiments of my invention but it is clear, that numerous changes 45 and omissions may be made without departing from the spirit of my invention.

I claim:

1. In a vaporizer for multi-stage service the combination of a float chamber provided with a 50 fuel nozzle, a primary mixing channel into which said fuel nozzle opens, a plurality of main atomizers each having an injector slot at its narrowest cross-section and being open on one side to the air and on the other side connected to the intake 55 manifold of the engine, each injector slot being connected to said primary mixing channel by a duct, a slot closure in the narrowest cross-section of each main atomizer and provided with splitting edges, the longitudinal axes of said main 60 atomizers being arranged substantially at right angles to the longitudinal axes of said ducts, whereby the flow of the primary mixture is deflected at said splitting edges, and conduits extending from said main atomizers. 65

2. In a vaporizer for multi-stage service as claimed in claim 1 a single slot closure controlling all main atomizers and adapted to open them successively.

3. In a vaporizer for multi-stage service in combination with the elements claimed in claim 1 Venturi nozzles in each duct connecting the injector slot with the primary mixing channel except the duct leading to the first stage arranged in a direction to throttle passage of compensating 70 75

air coming from the air-open end of the atomizer.

4. In a vaporizer for multi-stage service the combination of a float chamber provided with a fuel nozzle, a primary mixing channel into which 5 said fuel nozzle opens, a plurality of main atomizers of different sizes each having an injector slot at its narrowest cross-section and being open on one side to the air and on the other side connected to the engine, the main atomizer of 10 the first stage being the smallest in size, each injector slot being connected to said primary mixing channel by a duct, said ducts being of different sizes, corresponding to the sizes of the respective main atomizers, a single slot closure controlling the narrowest cross-section of all main 15 atomizers and provided with splitting edges, the longitudinal axes of said main atomizers being arranged substantially at right angles to the longitudinal axes of said ducts, whereby the flow of 20 the primary mixture is deflected at said splitting edges, extending from said main atomizers and having different sizes.

5. In a vaporizer for multi-stage service in combination with the elements claimed in claim 25 4, an adjustable stop adapted to limit the opening movement of said slot closure in such a manner, that the slot closure opens predetermined main atomizers.

6. In a vaporizer for multi-stage service, in 30 combination with the elements claimed in claim 4, throttling means disposed in each conduit beyond said main atomizers except the conduit of the first stage.

7. In a vaporizer for multi-stage service, in 35 combination with the elements claimed in claim 4, throttling means disposed in each conduit beyond said main atomizers except the conduit of the first stage, said throttling means being connected together and positively driven by means 40 of gears.

8. In a vaporizer for multi-stage service in 45 combination with the elements claimed in claim 1, an additional float chamber provided with a fuel nozzle opening into a duct leading to the primary mixing channel, a change-over element

at the point of junction between said primary mixing channel and said duct, said point being between the end of the primary mixing channel open to the air and the main atomizers.

9. In a vaporizer for multi-stage service in 5 combination with the elements claimed in claim 1, an additional float chamber provided with a fuel nozzle opening into a duct leading to the primary mixing channel, a change-over element 10 at the point of junction between said primary mixing channel and said duct, and means connected with said change-over element and driven by means of the pressure in the conduit of the first stage and adapted to move automatically the change-over element. 15

10. In a vaporizer for multi-stage service in combination with the elements claimed in claim 1, an additional float chamber provided with a fuel nozzle opening into a duct leading to the primary mixing channel, a change-over element 20 at the point of junction between said primary mixing channel and said duct, said additional float chamber having a second nozzle opening into a duct adapted to conduct idle mixture into the conduit of the first stage behind the slot closure. 25

11. In a vaporizer for multi-stage service in combination with the elements claimed in claim 1, an additional float chamber provided with a fuel nozzle opening into a duct leading to the primary mixing channel, a change-over element 30 at the point of junction between said primary mixing channel and said duct, said additional float chamber having a second nozzle opening into a duct adapted to lead idle mixture into the conduit of the first stage behind the slot closure and provided with an adjustable air admission aperture. 35

12. In a vaporizer for multi-stage service in combination with the elements as claimed in claim 40 1, an additional regulating valve arranged in said primary mixing channel behind the entrance of said fuel nozzle adapted to adjust the mixture.

ARNOLD SEIDEL. 45
